UNITED STATES PATENT OFFICE.

WILLIAM NICHOLS, OF PHOENIX, MICHIGAN.

SLIME-TABLE FOR CONCENTRATING ORES.

SPECIFICATION forming part of Letters Patent No. 257,056, dated April 25, 1882.

Application filed December 31, 1881. (No model.)

To all whom it may concern:

Be it known that I, WILLIAM NICHOLS, a citizen of the United States, residing at Phoenix, in the county of Keweenaw and State of Michigan, have invented new and useful Improvements in Slime-Tables for Concentrating Ores, of which the following is a specification.

This invention relates to that class of machines for concentrating ores which are composed of an inclined revolving table, around the circumference of which is arranged a perforated pipe for causing water to flow down the table, the ore deposited on the revolving table being carried around, and while so carried washed by means of the flowing water, the various particles of ore, according to their specific gravity, being carried a greater or less distance down the inclined table, whereby they are separated, the tailings and washed ore being received into separate receptacles arranged around the edge of a central opening in the table.

My invention has for its object to improve such construction of machines, and to produce an apparatus simple of construction which will separate and concentrate the ore or mineral and also the waste material in a perfect and efficient manner. This object I accomplish by the construction and arrangement of parts illustrated in the accompanying drawings, in which—

Figure 1 is a plan view of my table partly broken away, Fig. 2 a vertical section, and Fig. 3 a side view.

The letter R indicates the main supporting frame. Bevel bearing-wheels P are mounted in brackets g on the frame. An annular ring-frame, A, rests upon and revolves on the wheels P, the frame being provided with an annular track or way, a, in which the wheels run. The table-beams E rest upon and are secured to the ring-frame A and to the outer rim, F, of the table. The angle at which the beams E are set is regulated according to the material to be operated upon. Other annular cross-pieces F F rest upon the beams E, and over these cross pieces and the rim of the table is laid a suitable flooring or sheathing, G, of wood. A covering, H, of cloth, duck, raw-hide, rubber, leather, or any other similar suitable material, is placed over the sheathing G. A vertical flange, S', is secured on the outer

edge of the rim F, so as to form an annular groove or recess between it and the edge of the sheathing G. The outer edge, A', of the ring A is toothed or geared, and it and the table mounted thereon are rotated by a worm, B, on a shaft, D, which shaft is mounted in bearings on the frame R, and carries a pulley, C, on its end, which is driven by a belt at any required speed from any suitable power. A hub, I, having launders I' and L, in which the waste and ore are concentrated, is secured to frame R and fits snugly in central opening of table, as shown in Figs. 1 and 2. Discharge-pipes J J J lead from the waste-launders I' and a pipe, M, from the ore-launders L. The pipe M discharges into a trough, N, which carries the ore to any suitable receptacle; and the pipes J may discharge the waste into any vessel or trough.

A water-supply pipe, O, is supported above the revolving table, and is curved so as to hang within or over the annular recess S at the edge of the table. The bottom of this pipe is perforated, so that the water is discharged into the groove or recess S, which, when full, overflows and discharges a smooth film-like stream over the surface of the table. The supply of water will of course be regulated by a suitable stop-cock or valves at each end of the pipe. Another water-pipe, K, is arranged about parallel with the face of the table, and has a series of jet-pipes, k, which are curved or inclined toward the surface and center of the table, as shown in Fig. 1.

The material to be treated is delivered to the table at the points marked "Delivery" by any suitable means, and as the table is revolved in the direction of the arrow by the rack and worm the water supplied by the pipe O flows over the surface of the table and washes the waste material down into the launder or receptacle I', from whence it is discharged by the pipes J. As the table continues to revolve the ore on it, having been cleansed of the waste foreign substances, reaches the point under the jets k, and is by them washed down into the launder L, from whence it is discharged by the pipe M into the trough E.

It will thus be seen that the machine is continuous in its operation, the ore being treated continuously as it is placed or fed onto the

table; that the ore is concentrated in one receptacle, and that the waste is also concentrated, and may thus be very easily disposed of. The utility and practical advantages of thus concentrating the ore and waste in a continuous operation are great and obvious.

The covering of cloth or other material possessing a soft, rough, or fibrous surface, such as those above mentioned, readily catches the ore, which usually has sharp edges, but permits the waste to be washed down. By using such a covering I am enabled to incline the table steeper than otherwise, and thus insure the more thorough washing off of the waste.

15 The central portion, I^2 , of the hub I is elevated, as shown in Fig. 2, in order to prevent the ore and waste from being washed over it and escaping, and the lower edge of said hub is formed into an open offset, i , as clearly illustrated.

The open offset i above mentioned is provided so that any ore, waste, or water which may escape between the inner edge of the table and the band i' may fall into the launders I' and L .

25 Many modifications of the apparatus above described will doubtless readily suggest themselves to those familiar with this class of machinery without departing from the spirit of my invention. The table may vary in size according to circumstances and the character of work to be done. One ten feet in diameter is a very efficient size for most purposes.

Having thus described my invention, what I claim is—

35 1. The combination of the inclined table having the annular groove at its outer edge, mechanism for rotating the table, the perforated water-supply pipe which is supported in or above the annular groove in the table and discharges the water into the groove, ore and waste launders or receptacles at the inner edge of the table, and the water-jet pipes for washing the ore down the table into its launder, substantially as set forth.

40 2. The combination of the inclined table, means for revolving the same, the band i' , carried by said table, the hub I, and the annular receptacle constituting the launders I' and L , which receptacle extends out beyond the lower edge of the band i' to form the open offset i , substantially as described.

45 3. The combination of the main supporting-frame, the wheels thereon, the superposed ring-frame, and the inclined table carried thereby, the rack and worm, the water-supply pipes O and K, and the stationary hub having the ore and waste launders, substantially as set forth.

50 In testimony whereof I have hereunto set my hand in the presence of two subscribing witnesses.

WILLIAM NICHOLS.
